DISTRIBUTOR MEMBER FOR STOKERS

Edwin Archer Turner, New York, and Charles J. Surdy, Tuckahoe, N. Y., assignors, by mesne assignments, to The Standard Stoker Company, Inc., New York, N. Y., a corporation of Delaware

Application November 15, 1934, Serial No. 753,091

3 Claims. (Cl. 110—101)

Our invention relates to the distributor member for stokers of the type wherein a conduit communicates endwise with the firing opening of a boiler firebox. As the invention appertains to the distributor member and its associated parts, only so much of the remainder of the stoker mechanism is shown as is necessary to indicate the relation of the parts. The distributor member is exposed to the intense heat of the firebox. Because of this and due to cutting of the pressure fluid jet openings it must be replaced from time to time.

It is the main purpose of the invention to provide an improved and novel construction of the stoker conduit and the distributor member whereby the latter can be easily and readily removed from its position. Other objects of the invention reside in the specific form of the parts and in the particular fastening means employed to hold the distributor member in place.

On the drawing,

Figure 1 is a detail vertical section through the upright wall of a boiler firebox showing the device of the invention applied thereto in similar section;

Figure 2 is an elevation from within the firebox looking toward the firing opening; and

Figure 3 is a plan view of the structure shown in Figures 1 and 2.

Referring to the drawing, there is shown at 10 a portion of an upstanding wall of a boiler firebox having a firing opening 11 therein to which fuel is advanced by the screw 12 housed within the inclined stoker conduit 13 which opens endwise into the firing opening. The rectangular mouth portion 14 of the conduit extends entirely across the lower portion of the firing opening slightly above the lower marginal edge thereof to provide a space 15 between the bottom wall 16 of the conduit and that portion of the firebox wall forming the lower extremity of the firing opening.

Bolts 17 engaging the flanges 18 at the sides of the mouth portion 14, secure the conduit to the firebox in endwise communication with the firing opening. Fuel advanced by the screw 12 passes along the bottom wall 16 onto the chambered distributor or jet member 19 positioned in the firing opening. This jet member constitutes an extension of the bottom wall or floor 16 of the conduit and is separable therefrom. It extends from one side of the firing opening to the other and includes an upstanding front wall 20 having vertically and laterally spaced forwardly directed jet openings 21 communicat-

ing with the cored chambers 22, 23 for discharging pressure fluid fuel propelling blasts over and above the distributing plate 24. Pressure fluid is supplied to the chambers 22, 23 by supply lines 25 extending rearwardly from the jet member through the space 15 to a source of supply exterior of the firebox.

Any suitable means may be used for fastening the distributing plate 24 to the jet member 19 but for purposes of illustration the plate is shown as secured to the jet member by the countersunk cap screws 26 threaded into the ledge 27 of the jet member.

Preferably the floor 16, the flanges 18 and the conduit side walls 28 terminate in the plane of 15 the outside surface of the firebox wall 10. This insures a rigid construction of the conduit at its mouth portion where it is secured to the firebox and facilitates machining operations. The rear end of the jet member 19 abuts the front 20 end of the floor 16 and the top of the jet member lies in the same inclined plane as the floor. As shown the jet member 19 is wholly within the confines of the firing opening although in some instances it may be desirable to position the 25 front wall 20 at or forward of the inside surface of the firebox wall 10.

An improved construction is provided for securing the jet member 19 in position. For this purpose laterally spaced arms 30, one at each 30 side of the vertical medial plane of the firing opening 11, extend rearwardly and downwardly from the jet member 19 through the space 15 and at their lower ends are arranged in overlapping relation with the outside of the firebox 35 wall 10. The forked ends of the arms receive the studs 31 threaded in the firebox wall, and the washers 32 and the nuts 33 on the studs above the arms firmly secure the arms to the firebox wall and, together with the overlapping 40 relation of the arms and the firebox wall, maintain the jet member 19 in the position heretofore described.

The supply lines 25 are disposed between the arms 30 and both the supply lines and the arms 45 are beneath the floor 16 where they are protected by the conduit.

By merely loosening the nuts 33, the jet member 19 can be removed and replaced through the firing opening 11 without in any way disturbing the setting of the conduit or without dumping the fire.

In operation, fuel advanced by the screw 12 spreads laterally the full width of the conduit mouth portion 14 forming a fuel stream ad- 55

vancing into the firing opening 11 for substantially the width thereof and over the jet member 19. The fuel falls from the top of the jet member downwardly into the zone of action of the 5 pressure fluid blasts discharging from the jet openings 21 sweeping over the distributor plate, the ribs 34 of which aid in giving direction to the fuel.

Loss of fuel through the gaps 35 formed by 10 the rounded edges of the firebox wall is avoided by the plates 36 contacting the jet member 19 and constituting extensions of the conduit side walls 28 placed closely adjacent the sides of the firebox wall forming the firing opening. 15 These plates may be riveted to the conduit side walls and extend forwardly to the point of discharge of fuel from the conduit onto the propelling blasts and therefore protect the firebox wall from the abrasive action of the advancing 20 fuel stream.

While the plates 36 are above the jet member they do not interfere with its removal. When 25 the nuts 33 are loosened the jet member can be tilted downwardly to permit withdrawing the arms 30 through the space 15 and then pulled forwardly beyond the plates 36 and removed through that portion of the firing opening above the conduit 13, which portion, as is well known, is provided for hand firing and normally closed 30 by the firedoor 37.

As applied to the construction described, "forward", "forwardly" and similar terms are used with reference to the direction of travel of the fuel.

35 We claim:

1. In combination, a firebox having an up- 40 standing wall with a firing opening therein, a conduit exterior of the firebox communicating with the firing opening, the fuel supporting sur- 45 face of the conduit extending upwardly and forwardly to the lower portion of the firing opening, the discharge end of said conduit being dis- 50 posed above the lower marginal edge of the firing opening to provide a space therebetween, a chambered jet member in said firing opening spaced above the firebox wall defining the bottom of the firing opening and constituting an extension of the conduit, and means for rigidly securing said chambered jet member in spaced relation with respect to the firebox wall defining the bottom of said firing opening, said means including an

arm extending downwardly from said jet member across said space and overlapping the outside surface of the upstanding firebox wall beneath said firing opening, the lower end of said arm being shaped like a fork with the prongs thereof directed downward, said last named means also including a fastener received by the forked end of said arm for rigidly securing the latter to said upstanding firebox wall. 5

2. In combination, a firebox having an up- 10 standing wall with a firing opening therein, a conduit exterior of the firebox communicating with the firing opening, the discharge end of said conduit being disposed above the lower marginal edge of the firing opening to provide a 15 space therebetween, a chambered jet member in said firing opening constituting an extension of the conduit, and means for securing said chambered jet member to the upstanding firebox wall comprising a plurality of laterally spaced arms 20 extending downwardly from said jet member across said space and at their lower ends; each being shaped like a fork having downwardly directed prongs and arranged in overlapping relation with the outside surface of the firebox wall 25 and fastening members received by said forked ends of the arms firmly securing said arms to said firebox wall.

3. In combination, a firebox having an up- 30 standing wall with a firing opening therein, a 35 conduit exterior of the firebox communicating with the firing opening, the discharge end of said conduit being disposed above the lower marginal edge of the firing opening to provide a space therebetween, a chambered jet member in 40 said firing opening constituting an extension of the conduit, said jet member extending cross- 45 wise the full width of said firing opening, and means for securing said chambered jet member to the upstanding firebox wall comprising an arm at each side of the vertical medial plane of the firing opening extending downwardly from said jet member across said space and at its lower end being shaped like a fork having downwardly directed prongs and arranged in overlapping relation with the outside surface of the firebox wall and fastening members received by said forked ends of the arms firmly securing said arms to said firebox wall.
